UNITED STATES PATENT OFFICE

2,501,265

ROOF-NOSED TUYÈRE

Floyd C. Diaz, Charleroi, Pa., assignor to The American Steel and Wire Company of New Jersey, a corporation of New Jersey

Application February 13, 1948, Serial No. 8,169

2 Claims. (Cl. 266—41)

1

This invention relates to tuyères and more particularly to blast-furnace tuyères which are used to conduct pre-heated air or blast into a blast-furnace.

As is commonly known among blast-furnace operators, regardless of what type fuel is used, combustion or fusion takes place in the hearth of the furnace not more than about 35 inches beyond the nose of the tuyère. The fusion zone then extends upwards from the level of the tuyères because of the upward pressure of the blast. Regardless of how great the pressure of the blast being blown into the furnace, there is a limit to the pressure that can be built up proportionately in the hearth of the furnace below the tuyères. Heretofore, designers of blast-furnace tuyères have neglected to take into consideration this low-pressure area which is created on the under side of the tuyère when the blast is introduced into the furnace.

As the blast leaves the tuyère it is deflected sharply upward and becomes widely diffused. This diffusion takes place gradually as the blast penetrates the stock beyond the nose of the tuyère, the point of highest pressure being at the tuyère nose. In the normal operation of a blast-furnace, iron and cinder percolate down through the stock to the hearth as the weight thereof overcomes the blast pressure. Because of certain chemical and physical conditions of the furnace, furthermore, an accumulation of iron sometimes occurs, which does not penetrate the stock normally but falls suddenly to the hearth. This falling material sometimes drops into the region of fusion almost overcoming the blast pressure, but is deflected enough to miss the top of the nose of the tuyère by the high pressure of the blast present at that point. Below the top of the tuyère, however, the blast pressure falls off sharply so that material coming down so near the tuyère is apt to strike the bottom of the tuyère because of the low-pressure area existing there. The bottom of the tuyère is thus subject to severe abuse and this condition accounts for most of the damage suffered by tuyères during furnace operation. It makes frequent replacement of tuyères necessary and involves a consequent loss in production.

The principal object of my invention is to provide a blast-furnace tuyère having means for protecting the bottom from damage as described above so that it will have a much longer life.

Another object of my invention is to provide a tuyère with a nose having an overhang or projection extending around the upper portion and

2

affording a roof-like surface protecting the bottom.

Another object of my invention is to provide a tuyère that will project the blast farther inwardly and shift the point of maximum pressure, thereby protecting the bottom of the tuyère from falling material by deflecting it toward the center of the hearth.

Still another object of my invention is to provide a tuyère having a nose with an extended roof portion of increased thickness designed to withstand more effectively the wear resulting from abrasion by the hot blast.

These and other objects will become more apparent after referring to the following specification and the accompanying drawings, in which:

Figure 1 is a partial vertical section through the hearth and bosh of a blast-furnace having the tuyère of my invention installed therein;

Figure 2 is a central vertical section through the tuyère taken along the plane of line II—II of Figure 3;

Figure 3 is an elevation of the tuyère looking toward the nose; and

Figure 4 is an elevation of the rear end of the tuyère.

Referring in detail to the drawings, Figure 1 shows a blast-furnace 10 supported on a plurality of columns 11 and including a bosh 12, and a hearth 13 having tuyères 14 installed therein subjacent the lower bosh line. Hot blast is supplied to the tuyères from a bustle pipe 15 through tuyère stocks 16 and below pipes 17. This construction is conventional except for the novel tuyère of my invention, the details of which will now be described.

Referring more particularly to Figures 2 through 4, my improved tuyère 14 has the usual central air passage 18 therethrough. The nose 40 or discharge end 19 has an overhang or projecting roof 20 extending around the upper portion thereof. As shown, the roof projects a substantial distance beyond the bottom of the nose designated 21. The tuyère is generally frustoconical in shape having spaced inner and outer walls providing a cooling chamber 22. The cooling chamber extends in its upper portion into the roof of tuyère 14. The fluid coolant is introduced through an inlet 23 into a passage defined by spaced parallel ribs terminating adjacent the nose so that the incoming water is directed to the roof portion of the tuyère. An outlet for the cooling chamber is provided at 24.

Openings 25 and 26, which may be plugged or opened, are provided so that they can be used

either as water outlets to vary the water circulation in the tuyère body or for clean-out purposes.

In order to further insure the tuyère a long life, the thickness of top wall 21 of the roof portion 20 is made greater than that of the walls of the tuyère body.

In operation, roof 20 of tuyère 14 functions to advance the high-pressure point of the blast entering the furnace a substantial distance beyond the high-pressure point of known tuyères, thereby extending the fusion zone far enough away from the bottom of the tuyère nose 21 so that the pressure of the blast will deflect away therefrom any falling material, thus practically eliminating the possibility of damage to the tuyère.

While one embodiment of my invention has been shown and described, it will be apparent that other adaptations and modifications may be made without departing from the scope of the following claims.

I claim:

1. A blast-furnace tuyère comprising a frustoconical body having an air passage therethrough, an overhanging roof portion projecting from said body, said roof portion extending from substantially the center line in a horizontal plane to the top of said body, the top wall of said overhanging roof portion being substantially greater in cross-section than the other walls of said body, said body having spaced inner and outer walls defining a cooling chamber surrounding said air passage substantially along its length and ex-

tending into said overhanging roof portion, and a longitudinal channel in the upper portion of said cooling chamber, said channel extending horizontally toward said overhanging roof portion from an inlet opening in the face of said body opposite said overhanging roof portion.

2. A blast-furnace tuyère comprising a frustoconical body having an air passage therethrough, an undercut bottom portion on the nose of said body extending downwardly and inwardly from substantially the longitudinal center line of said body, the top wall of the nose of said body being substantially greater in cross-section than the other walls of said body, said body having spaced inner and outer walls defining a cooling chamber surrounding said air passage substantially along its length, and a longitudinal channel in the upper portion of said cooling chamber, said channel extending horizontally toward the nose of said body from an inlet opening in the face of said body opposite its nose.

FLOYD C. DIAZ.
